RATION OF MASSACHUSETTS.

LABELING-MACHINE.

1,301,015.

Specification of Letters Patent.

Patented Apr. 15, 1919.

Application filed October 28, 1918. Serial No. 259,954.

To all whom it may concern:

Be it known that we, HERMAN STAKE and ARVID P. EKVALL, citizens of the United States, residing at Worcester, in the county of Worcester and State of Massachusetts, have invented certain new and useful Improvements in Labeling-Machines, of which the following is a specification.

This invention relates to certain improvements in the construction and organization of mechanism for automatically delivering packages of the character described, and affixing labels thereon; the object being to provide a convenient, efficient and economical means whereby flat boxes, packages or containers having a plain, depressed or sunken, panel surface, may be successfully and rapidly labeled.

Another object is to provide a novel organization of mechanism adapted for automatically applying pressure for affixing labels upon the face of containers such as sardine-boxes or the like, by contact in a direction approximately perpendicular to the labeled surface.

Another object is to provide, in a machine for the purpose specified, novel label-presser mechanism and means for actuating the same, in synchronous relation to the label-presenting mechanism and intermittent package-feeding means.

Other objects and features of our invention will be understood from the following detailed description, the particular subject matter claimed being hereinafter definitely specified.

In the accompanying drawings, (three sheets) referred to as a part of this specification, like reference characters denote like parts of the mechanism on the several views.

Figure 1 represents a side elevation of a labeling machine embodying our invention. Fig. 2 is a detail view of the intermittent-drive mechanism for the package delivery chain. Fig. 3 is a front elevation of the machine. Fig. 4 is a plan view especially showing the label-pressers and presser-actuating means; some of the cams and parts of the labeler actuating mechanism being omitted for clearer illustration. Fig. 5 is a front view of the pressers and their actuating means, separate from other parts. Fig. 6

illustrates the relative forms of the presser-controlling cams upon the operating shaft. Fig. 7 is a fragmentary plan view showing a portion of the package-supporting way as provided with springs or frictional devices for retention of the package at labeling position. Fig. 8 is a cross-section of the run-way and delivery chain, and Fig. 9 is a cross-section of the run-way and discharge chains in rear of the chain driving sprocket.

Referring to the drawings, numeral 1 denotes the frame of suitable construction for supporting the various working parts, and is preferably provided with a pedestal, base or column 11 having a broad outspread foot as shown. 2 indicates the main operating shaft provided with a clutch connected pulley or wheel P, to which the motive power is applied in any well known or suitable manner. 3 indicates the vertically reciprocating picker-carrier operated up and down by the lever 4 actuated by a cam 4^a, mounted on the shaft 2; and 5 indicates the label-pickers supported upon said picker-carrier. H denotes the label-supply holder for containing a pack of labels L of the desired form, 80 which are taken individually from the bottom of the pack by contact therewith of the gummed top surfaces of the picker plates 5, and presented thereby in position for affixment to the box or article to be labeled. 85 Numeral 6 indicates the gum-box or reservoir for containing the supply of gum, glue or other adhesive; and 7 the gum-delivering roll rotated within said gum-box by the chain 8 and suitable drive-sprockets, and 10 the gum transfer roll which is supported upon arms 9 to swing to and from the delivery roll 7 and to roll across the faces of the pickers 5 during their upward movement for charging said pickers with adhesive. 90

12 indicates a swinging grip-device for temporarily clamping the label to the package and releasing it from the pickers. Said grip-device is attached to an oscillatable shaft 13 journaled in the frame and operated by an arm and connection 14 actuated by a cam upon the operating shaft 2. 95

The above described parts, in their relative arrangement and action, are substantially the same as heretofore employed in 100 practice; and are not, in so far as such prior employment is involved, means of our 105

invention; but our invention has reference to such means as an element of combination with other devices in a new organization of mechanism for effecting further beneficial results.

For supporting flat surfaced or paneled boxes B, or the article to be labeled, we arrange a run-way frame 15 of the character illustrated extending through the machine from front to rear, beneath the label-applying devices; its ends projecting for a convenient distance, as best shown in Fig. 1. Said run-way is provided with tracks or ledges 16 upon which boxes or packages slide, and with upright parallel side guards 17 for keeping the same in alinement.

Sprocket wheels or sheaves 19 and 20 are rotatively mounted at the respective ends of the run-way, and a triple sprocket 21, or group of three sprocket-wheels (see Fig. 4) is located at an intermedial position, somewhat rearward from the labeling position, and fixed upon a driven shaft 22 arranged transverse to the run-way, parallel with the operating shaft 2, and supported to turn in suitable bearings 23 mounted upon the frame, or upon brackets attached thereto.

A delivery chain 25 passes around the front sprocket 19 and central member of the triple sprocket, or the intermediate group 21, and a pair of discharge chains 26 and 26⁺ are arranged around the side sprockets of the intermediate group and around the sprockets 20 at the rear part of the run-way. The upper reach of said chains approximately coincides with the plane of the tracks or run-way surface, and the delivery chain 25 is provided at predetermined intervals with projecting lugs or pusher detents 27, suitable for propelling the boxes along the run-way tracks. The discharging chains may be without lugs or detents. The rear end of the run-way preferably terminates with a discharge table or inclined chute 28. The tracks at the rear of the triple sprocket are depressed slightly below the normal level of the preceding portion, and the run-way is formed with grooves 17⁺ (see Fig. 9) upon the bottom of which the chains slide, being thereby upheld from sagging so as to sustain the boxes upon the chains while carried to the discharge table. Yieldable brake devices or flat springs 18 are arranged at the inner faces of the side guides 17 at the labeling position, which frictionally keep the box B in place for receiving its label and prevent its being projected beyond the desired place by momentum acquired from the quick movement of the delivery chain.

The housings in which the sprockets 19 and 20 are journaled, are preferably arranged, for endwise adjustment upon the run-way frame for regulating the tension on the chains. The shaft 22 has a gear 24

fixed thereon, that meshes with a gear 29 arranged upon a shaft or axis support 30, which also has a radially slotted Geneva element 31 mounted thereon and connected with said gear; and which is engaged by a disk 32 and wrist-pin 33 that are mounted upon and revolve with the operating shaft 2; said parts serving for imparting intermittent movement to the triple sprockets 21 and chains 25 and 26 as the operating shaft revolves, and the pin 33 passes into and from the slot of the Geneva element; thereby advancing the chains with a step-by-step movement in synchronous relation with the actions of the label-delivering mechanism, and for a predetermined distance equal to the spaces between the detents 27 on the delivery chains.

At or near the front end of the run-way there is a chute or cage 35 preferably consisting of a set of upright stakes or guides adapted for inclosing a stack of unlabeled boxes in position to move down upon the delivery chain 25, whereby the boxes are taken, one at a time, from the bottom of the stack by the respective lugs 27, and thereby carried to the position for receiving its label.

An important feature of our invention is the novel organization of means for pressing the label upon the flat or paneled surface of the box or article to be labeled, by pressure applied in a direction approximately perpendicular to the plane of the surface. This means comprises a pair of oppositely arranged presser levers 36 provided with presser faces or pads 37 upon their inner ends. Said levers 36 are pivotally fulcrumed upon the upwardly extended arms of angle levers 38, which in turn are fulcrumed as at 39, upon rigid brackets 40 attached to the run-way frame 15 and projecting outward at each side thereof. The outer ends of the presser levers 36 are joined by pivotally attached links 41 with the outer ends of the swinging lever or member 42 110 fulcrumed at a position intermediate their length, preferably upon the same axis-pin 39 as the angle levers; said axis-pin being supported between two projecting arms on the bracket 40. The links 41 are best made adjustable in respect to their length, and yieldable; each being provided with a spring 43 adapted to maintain their normal extension, but to yield under any excess pressure. The inner ends of the swinging levers 42 are 120 connected by pivotally attached links 45 with a cross-head fixed to an upright movable rod or slide-bar 46; while the inner arms of the angle-levers 38 are in similar manner connected by links 47 with a cross-head fixed upon a rod or slide-bar 48 arranged adjacent to the first mentioned rod. The slide-rods 46 and 48 are fitted in guides or openings in the upper and lower members of a bearing frame 1⁺ at the front of the 130

main frame of the machine; and are arranged to move up and down therein with an endwise reciprocal action.

Dual oscillatable members, preferably arranged as a horizontal shaft 50 having a tubular sleeve 51 thereon, are supported in bearings upon the frame 1*. Said oscillatable members are each provided with two arms disposed thereon in approximately right angular relation. One arm on the shaft 50 is connected pivotally, or by link 52, with the slide-rod 46; while its other arm is pivotally united to an operating connection 53. Likewise, one arm on the sleeve or oscillatable member 51 is connected pivotally, or by link 52* with the slide-rod 48 which actuates the presser-levers 36; while its other arm is pivotally attached to a second operating connection 54, as illustrated. The operating connections 53 and 54, which consist of endwise moving bars, are actuated by cams 56 and 57 mounted upon and revolving with the operating shaft 2. The rear end of said bar is preferably furcated to embrace the shaft as a guide, (see dotted lines Fig. 1) and is provided with a stud-roll 55 that engages the face of the cam. Springs 58 and 59 are suitably connected with the respective bars 53 and 54, and to an anchorage fixed on the frame; said springs serving to keep their stud-rolls in contact with the cams, and for moving the bars in one direction as controlled by the cams. The relative forms of the cams are shown in Fig. 6.

The operation is as follows: Assuming that the label-holder H contains a supply of labels; that the gum-box 6 has a quantity of glue or similar adhesive material therein; and that the machine is in action; the boxes or packages B are stacked in the cage 35 above the delivery chain 25. At each revolution of the labeler operating shaft 2 the wrist-pin 33 engages a slot of the Geneva element 31 and causes a partial revolution of the gears 29 and triple sprocket 21, and thereby effects an intermittent movement of the chains 25, 26 and 26*. A detent 27 of the chain 25 takes the packages B singly from the bottom of the stack and advances them to the labeling position in time to receive the label L which is brought down from the label-supply pack L by the gum-applying pickers 5, and centrally clamped to the package by the swinging grip-device 12. The connections 53 and 54 then being actuated by the cams 56 and 57 effect, by oscillation of the shaft 50 and sleeve 51, a downward movement of the slide-rods 46 and 48, the former slightly in advance of the latter. Such movements cause the angle-levers 38 to swing the presser-levers 36 from their outward spread position (see Fig. 3) inward to position where their presser pads 37 are over the label and package; while the immediately

following action of the slide-rod 48 and its connections tilts the levers 42 and 36 on their fulcrums and thereby brings the presser pads 37 down upon the label, pressing it upon the depressed or sunken panel surface within the protruding rim of the box or package B, such as are usually formed on sardine containers and similar flat packages; the pressure being exerted thereon in a direction perpendicular to the plane of the flat surface, the contact being maintained without lateral effect.

As the operating shaft and cams 56 and 57 further revolve, movement of the connections 53 and 54 and oscillative members 50 and 51 is reversed, thereby respectively moving the slides or rods 46 and 48 upward; this action by the rod 46 and intervening parts causes the presser-levers 36 to tilt so as to lift the presser-pads 37 away from the label, while the action by the rod 48 and links 52 throws outward the fulcrum-supporting arms of the angle levers 38, thereby laterally retracting the presser members to spread position, as shown in Fig. 3. At the next movement of the chain actuating mechanism the labeled box or package is transferred to the discharge chains 26, 26*, and another box or package is brought into position beneath the label-affixing members and the operation repeated.

What we claim is—

1. A machine for labeling flat or paneled-face boxes or the like, including a bottom delivery label-supply holder, vertically moving pickers, means for gumming said pickers, a grip-device acting between said pickers, a box-supporting run-way extending beneath the pickers, a traveling delivery chain provided with detents for propelling the boxes along said run-way, means for intermittently actuating said chain, a pair of tiltable presser-levers having face members disposed for pressing the label upon the package in a direction approximately perpendicular to its surface, right and left oppositely swinging fulcrum-carrying members having the fulcrum of said presser-levers respectively carried thereon, supports at the sides of the run-way for the fulcrums of said carrying members, means for actuating said carrying members and presser-levers independently, and means for operating the label-delivering mechanisms, box-delivery mechanism, and presser devices with a relative synchronous action.

2. In a machine of the class described, the combination, with means for gumming, delivering and clamping a label, a package-supporting way, and means for automatically presenting a package in position for receiving its label and for removing said package therefrom; of label-pressing devices adapted for giving a non-wiping pressure upon the label, including a tiltable

presser-lever fulcrumed for up and down action of its pad or pressing face, fulcrum-supporting means adapted for carrying the fulcrum of said tiltable presser-lever laterally in respect to the package-supporting way, mechanism for imparting an independent movement to said fulcrum-supporting means, and to said tiltable presser-lever, and means for operating said parts synchronous with the label-applying mechanisms.

3. A machine for labeling flat packages of the character described, including means for gumming, delivering and clamping a label upon a panel or flat surface, a run-way having package-supporting tracks and upright package-supporting tracks and upright side guides extending underneath said label-delivery means, a package supply upon said run-way, an intermittently actuated chain adapted for moving packages along the tracks to the label-receiving position and away therefrom, yieldable devices at the sides of the run-way for positioning or detaining the package for receiving its label, laterally oscillatable fulcrum supporters at opposite sides of the run-way, tiltable presser arms fulcrumed thereon and having their presser-faces adapted for pressing the label to the flat surface of the package with a non-wiping contact approximately perpendicular to the plane of its surface, and means for actuating said fulcrum supporters and said pressers.

4. In a machine of the class described, in combination with means for positioning a package, and means for gumming and placing a label thereon; a presser device comprising a tiltable presser-lever having a presser-pad at its inner end, a laterally swinging fulcrum-carrier having said presser-lever fulcrumed thereon, an auxiliary lever below said presser-lever, stationary fulcrum bearings for said carrier and said auxiliary lever, a yieldable link connecting the outer arms of the presser-lever and auxiliary lever, a spring arranged for normally extending said link, and actuating means respectively connected for moving said fulcrum-carrier and said auxiliary lever with independently controlled synchronous action.

5. In a machine of the class described, the combination, with means for gumming, delivering, and clamping a label upon a box or package having a flat or paneled surface, means for supporting said package, comprising a run-way with bottom tracks and guiding side members, and means for positioning the package to receive its label; of label-affixing presser devices, including a pair of transversely arranged levers having elastic presser-pads at their inner ends adapted for contact with the label approximately perpendicular to the plane of its surface, angle levers having their fulcrums supported at the sides of the run-way, their

upward arms carrying the fulcrums of said presser-levers, a pair of reciprocating slides, cam-controlled means for operating said slides individually, intermediate connecting members uniting the arms of the respective presser-levers with one of the slides, and means uniting the inner arms of the angle-levers to the other slide, for operation substantially as set forth.

6. In a machine for the purpose described, a presser mechanism comprising in combination, a package-supporting element, a pair of upwardly and downwardly swinging presser-levers having face members for pressing the label upon the package, a pair of angle-levers fulcrumed upon brackets attached to the package-supporting element, and having the fulcrums of the presser-lever carried upon their upwardly extended arms, auxiliary tilting levers fulcrumed upon said brackets and having their outer ends linked to the outer ends of the presser-levers, a pair of upright end-wise movable slide-members, guide means therefor, links connecting the head of one of said slide-members to the respective auxiliary tilting levers, links connecting the head of the other slide member to the respective inwardly projecting arms of said angle-levers, an oscillating shaft supported in bearings on the frame and having an arm connected for moving the slide-member that actuates the auxiliary levers and presser-levers, an oscillating shaft or sleeve having an arm connected for moving the slide-member that actuates the angle-levers, connecting-bars respectively pivoted to arms fixed on said shaft and sleeve, a rotating operating shaft, and cams mounted upon said shaft for effecting and controlling the movement of said connecting-bars.

7. In a labeling machine, the combination of a run-way comprising parallel side guides and tracks for supporting flat boxes or the like, a delivering chain centrally along said run-way, a pair of discharge chains, chain-supporting sheaves at the ends of the run-way, an intermediately positioned triple sprocket-wheel operatively engaging said chains, means for gumming and delivering labels including a label supply, a gum supply, vertically reciprocating picker-carrier having gum-applying picker-plates thereon, and a means for transferring gum to the picker surfaces, oppositely disposed presser members each comprising a swing-lever and an angle-lever fulcrumed upon stationary supports at either side of the run-way, and an oscillatable presser-lever centrally fulcrumed upon the arm of said angle-lever and having its outer end linked to the outer arm of said swing-lever, and means for independently actuating said angle-lever and said swing-lever.

8. In a labeling machine, in combination with label-applying mechanism, including

- the label-supply holder, vertically reciprocating pickers, picker-gumming means, a grip-device, an operating shaft with means for actuating the pickers, gumming and grip device, a package-supporting run-way extending beneath said pickers, a delivery chain and discharge chains traveling along said run-way, a shaft extending across the run-way frame, sprockets mounted on said shaft and carrying said chains, a gear fixed on said shaft, an intermediate gear meshing therewith connected with a Geneva element mounted on an axis support below the run-way, and a revolving disk and wrist-pin carried by the operating shaft and engaging said Geneva element for intermittently actuating said chains, label-affixing presses adapted for downward pressure upon the packages, laterally retractable supports for said presses at the sides of the run-way, and intermediate mechanism for controlling said presses actuated by cams mounted upon said operating shaft.
9. In a labeling machine, the combination with means for delivering, gumming and affixing labels, a support for a box or article to be labeled, consisting of a guide-way having tracks whereon the articles slide, means for supporting a stack of boxes for delivery thereto, a delivery chain provided with detents movable along the center of said guide-way, a pair of discharge chains, guide wheels for said chains at the respective ends of the guide-way, a triple drive-sprocket carrying said chains at an intermediate position, and means actuated from the operating shaft for intermittently rotating said drive-sprockets, said parts being constructed and organized for operation substantially as set forth.
10. In a labeling machine, in combination with label-applying mechanism, including the label-supply holder, reciprocating pickers, picker-gumming means, a grip-device, the main operating shaft, and means for actuating said pickers and grip-device; a work-supporting run-way extending beneath said pickers, a delivery chain, a pair of dis-
- charge chains, a triple-sprocket carrying said chains, a shaft therefor extending across the run-way frame, a gear fixed on said shaft, an intermediate gear meshing therewith and joined with a Geneva element mounted on an axis support below said run-way, and a revolving disk and pin carried by the main operating shaft and engaging said Geneva element for intermittently actuating said chains, label-affixing presser mechanism supported at the sides of the run-way frame, said presses being adapted for exerting direct downward pressure upon the label and package, and retractable laterally beyond the path of the pickers, and means for actuating said presser mechanism controlled by cams upon the labeler-operating shaft.
11. In a machine of the character described, in combination with label-applying instrumentalities, a package-supporting means consisting of a run-way frame disposed horizontally beneath the label-delivery position and extending at front and back thereof; said run-way comprising upstanding side guides of said run-way, tracks whereon the packages slide, and an intervening groove in the bottom of said run-way, package supply cage mounted upon the run-way, an endless chain moving in said intervening groove and provided with detents that pass beneath said cage, sprocket-wheels supporting and operating said chain, edge-embracing members at the sides of the run-way, for locating and temporarily detaining the package to receive its label, presser mechanisms at the opposite sides of the run-way, having presser members with faces that flatly contact with the plane of the label upon the package while detained at position by said side embracing members, and means for operating said parts.

Witness our hands this twenty fourth day 90
of October, 1918.
